UNITED STATES PATENT OFFICE.

JOHN T. DORFF, OF DUNDALK, MARYLAND.

SHOE.

Application filed August 26, 1922. Serial No. 584,453.

To all whom it may concern:

Be it known that I, JOHN T. DORFF, a citizen of the United States, residing at Dundalk, in the county of Baltimore and State of Maryland, have invented a certain new and useful Improvement in Shoes, of which the following is a full, clear, and exact description.

This invention relates to shoes, particularly shoes for rolling mill workers, foundrymen and others who work on heated floors or in a heated atmosphere.

One of the most serious discomforts to which such workmen are subjected is the excessive heating of the feet. To protect their feet such workmen have heretofore worn heavy shoes with very thick soles. Such shoes, while they protect the feet to some extent, have the disadvantage of being clumsy, and also the disadvantage that when they once become heated they retain the heat and become very uncomfortable. It is the main object of this invention to provide a shoe which will effectively protect the feet of the wearer against excessive heat. A further object is to provide a shoe which is heat resisting and at the same time light and comfortable. A further object is to provide a heat resisting structure which is adapted to be built up about any ordinary shoe.

The following description and annexed drawings set forth in detail certain means embodying the invention, the disclosed means, however, constituting but one of the various mechanical forms in which the principle of the invention may be employed.

Reference should be had to the annexed drawings forming a part of this specification, in which Fig. 1 is a perspective view of the shoe; Fig. 2 is a side elevation thereof; Fig. 3 is a transverse section through the forward portion of the shoe.

Referring to the drawings, I have shown a shoe of ordinary construction comprising an upper 11, to which is secured the sole 12 and heel 13. Secured to the sole 12 is an auxiliary sole 14 which may be formed from leather or from a heat resisting composition. The auxiliary sole 14 is spaced from the outer sole 12 by means of a series of spaced transverse cleats 15. The cleats 15 may be nailed to the outer sole 12 and the auxiliary sole 14 may be nailed through the cleats 15 to the outer sole. The spaced cleats 15 form air passages between them, allowing free

passage of air between the outer and auxiliary soles. The cleats 15 are preferably formed of rubber or some other resilient material in order to make the sole flexible and springy. If desired, a layer 16 of asbestos or other heat resisting material may be secured between the cleats 15 and the outer sole 12. An auxiliary vamp 17 is secured along its lower edges between the sole 12 and upper 11 and extends from adjacent the front edge of the heel over the arch and toe of the shoe. The auxiliary vamp 17 fits loosely over the body of the shoe so that an air space is provided between the shoe upper and the auxiliary vamp. The auxiliary vamp is slit centrally at the arch to provide edges which conform to the edges of the lacing flaps of the shoe, and lacing eyelets 18 secure the auxiliary vamp 17 to the upper 11 along the edges of the lacing flaps. The rear edges of the auxiliary vamp 17 extending from adjacent the forward edge of the heel to the slit portion thereof are unattached so that air is free to circulate between the auxiliary vamp 17 and the upper 11 around the sides and over the toe thereof. By reason of the free circulation of air between the outer and auxiliary soles 12 and 14 very little heat will be transmitted to the outer sole 12 with which the foot of the wearer contacts, and by reason of the air space between the shoe upper 11 and the auxiliary vamp 17 very little heat can be transmitted through the upper to the foot of the wearer.

Having described my invention, I claim:—

1. A shoe comprising an upper and an outer sole, an auxiliary sole of flexible non-metallic material said soles being formed of materials which are poor conductors of heat, a series of transverse flexible cleats interposed between the outer and auxiliary soles and extending from one edge to the other of said soles, and forming air passages for the free circulation of air between them, and means for attaching the soles and cleats together.
2. A shoe comprising an upper, an inner sole secured to said upper, an outer sole secured to said inner sole, a series of spaced cleats between said inner and outer soles, said soles and cleats being formed of materials which are poor conductors of heat, and a layer of asbestos between said cleats and inner sole.
3. A shoe comprising an upper, a sole se-

cured to the upper, and an auxiliary vamp secured to said sole and overlying and spaced from the upper, said auxiliary vamp being unattached along its rear edge whereby air ⁵ is free to circulate between the auxiliary vamp and shoe upper.

4. A shoe comprising an upper, a sole secured to the upper, and an auxiliary vamp covering the toe and arch portions of the ¹⁰ shoe and spaced therefrom, said auxiliary vamp being secured along its edges to the sole from adjacent the heel around the toe, the rear edges of said auxiliary vamp on opposite sides of the shoe being unattached

whereby air is free to circulate between said ¹⁵ auxiliary vamp and shoe upper.

5. A shoe comprising an upper having lacing flaps, a sole secured to the upper, an auxiliary vamp secured to said sole and overlying and spaced from the toe and arch portions of said upper, said auxiliary vamp having flaps corresponding to the flaps of the upper, and lace receiving eyelets securing the flaps of the auxiliary vamp to the flaps of the upper. ²⁰

In testimony whereof, I hereunto affix my signature.

JOHN T. DORFF.
